UNITED STATES PATENT OFFICE.

ISAAC Q. GURNEE, OF BUTLER, NEW JERSEY, AND ALBERT A. SMITH, OF NEW HAVEN, CONNECTICUT, ASSIGNEES TO SUPERIOR HARD RUBBER COMPANY, OF BUTLER, NEW JERSEY, A CORPORATION OF NEW JERSEY.

SPRAY SYRINGE.

Application filed October 20, 1922. Serial No. 595,785.

To all whom it may concern:

Be it known that we, ISAAC Q. GURNEE and ALBERT A. SMITH, citizens of the United States, residing at Butler, in the county of 5 Morris, and State of New Jersey, and at New Haven, county of New Haven and State of Connecticut, respectively, have invented certain new and useful Improvements in Spray Syringes, of which the following is a specification.

This invention relates to an improved syringe; particularly a syringe intended for irrigating and flushing out the internal cavities and passages of the human body.

15 An object of this invention is to provide a syringe capable of discharging a liquid in the form of a spiral spray, and of such construction that the inside parts through which extend the outlet ducts of the delivery nozzle of the syringe are tightly and permanently secured to the nozzle in such a manner that all risk of their getting loose and becoming detached is entirely obviated, the nozzle and all its parts and in fact the complete syringe being constituted of a material 25 that will at no point afford a lodgment to dust, dirt or any other foreign substances, either within or upon the surface.

Other objects and advantages of this invention will appear in the following description, taken with the accompanying drawings, upon which the preferred embodiment of our invention is illustrated, and the novel features of our invention are defined in the appended claims. But this disclosure is explanatory only and we may make changes falling within the scope and spirit of the invention to the full extent indicated by the broad and general meanings 40 of the terms in which the claims are expressed.

On the drawings:

Figure 1 is a side view of a syringe of the type to which our invention belongs; 45 Figure 2 is a side elevation on a larger scale of the delivery nozzle of the syringe; Figure 3 is a front view of said nozzle; Figure 4 is a section on the line 4—4 of Figure 3; 50 Figure 5 is a front elevation of the inside core of the nozzle, carrying the outlet ducts and having a deflector or head for directing the jets from the ducts away from the axis of the nozzle.

Figure 6 is a side view of said core; and 55 Figure 7 a rear view thereof.

The same numerals identify the same parts throughout.

In the particular description of the drawings we use the numeral 1 to indicate a tube 60 or pipe, preferably of hard rubber, bearing at one end a rubber bulb or reservoir 2, and at the other a delivery nozzle including a tip 3. The bulb 2 can be secured to the pipe 1 by having a neck which is slipped over a flange, not shown, at the extremity of the tube 1, in the usual way, and the tip 3 at the opposite extremity is preferably detachable so that it can be dismounted for inspection and cleaning.

70 This tip 3 has a form of a tubular section from one end of which projects a reduced threaded neck 4; there being a shoulder 5 at the union of the neck 4 with the body of the tip so that when the tip is screwed into the end of the tube 1, which is provided with internal threads to be engaged by the threads on the outside of the neck 4, the shoulder 5 will abut the extremity of the tube 1 and form a joint or seam which can 75 be made as tight as necessary. Through the neck 4 extends a bore 6 which may be approximately of the same diameter as the bore through the tube 1, and inside the body of the tip 3 is a larger bore 7 which communicates with the bore 6 and which extends from the open mouth of the tip inward as far as the internal shoulder 8. The tip 3 receives and has secured therein a core 9 of 80 such construction that when the bulb 2 is filled with liquid and then compressed, the liquid will be expelled from the syringe around the inside of the rim of the tip 3, and in the form of a number of separate streams which take a helical direction and at the 85 same time fly away from the axis of the tip, and unite to form a voluminous spray, globular in form, and consisting of a number of spiral jets of liquid that will sufficiently reach and cleanse all the parts to which the 90 liquid is supplied. The tip 3 and core 9 constitute the outlet nozzle of the syringe.

95 One part of the core 9 is in the form of a cylindrical disk or button 10 of less thickness than the distance between the shoulder 8 and the rim at the open mouth of the tip 3. In the cylindrical surface of this disk 10 are 100 fashioned a number of cuts or recesses 11,

these recesses 11 being spaced at equidistant intervals apart around the circumference of the disk, and being diagonally arranged; so that they will not be parallel with the axis 5 of the tip, but will extend spirally with respect thereto when the core is thrust inside the tip 3. These recesses 11 will thus afford a number of outlet ducts through which the liquid flowing through the nozzle 10 must pass before it can escape from the syringe. On the side of the disk 10 that is to lie adjacent the shoulder 8 is a projection or knob 12 which will extend into the adjacent end of the bore 6 and at the opposite 15 side of the disk 10 the core will be provided with a head 13 in central position and of larger diameter than the projection 12. This head presents to the adjacent face of the disk 10 a conical surface 14 so that as 20 the separate streams of liquid escape from the outlet ducts 11 they will strike the surface 14 and be directed away from the axis of the nozzle. The head 13 and projection 12 may be in one piece, the projection making 25 a shank or neck for the head, and passing through a central opening in the disk 10.

The tip 3 receives the core 9 in such a manner that all risk of the core 9 becoming loose in the tip or detached is completely 30 obviated. As shown in Figure 4, the disk 10 will occupy such a position that there will be a small space between the shoulder 8 and the adjacent face of the disk; and the projection 12, which will be of less diameter 35 than the inside of the bore 6, will just enter the mouth of the bore 6. With the tip 3 and core 9 constructed of hard rubber, for example, the tip 3 after being molded can be softened; then the core 9 can be pushed 40 into the mouth of the tip the required distance. When so inserted the core 9 will be in hardened condition and will snugly fit the tip 3, which is usually softened by heating and therefore expanded somewhat. 45 After receiving the core 9, the tip is then cooled and hardened again, and the contraction which it undergoes makes it engage the core so tightly that the core cannot afterwards come out. In a similar manner the 50 disk 10 can be shrunk on the shank, making the projection 12.

The syringe can be provided with the

usual rubber guard 15, mounted on the pipe 1 in front of the bulb 2. To fill the syringe, the nozzle can simply be taken off and the 55 bulb collapsed so as to allow it to draw in through the tube a full charge of liquid. This method enables the bulb to be filled more quickly, and then the replacement of the nozzle makes the syringe ready for use. 60 Pressure upon the bulb 2 will force the liquid through the pipe 1 and bore 6 into the enlarged bore 7 of the nozzle, between the disk 10 and the shoulder 8. There the liquid will spread out and flow through the ducts 65 11; and as it escapes from these ducts at high velocity, the action of the conical surface 14 will force the jets outward away from the axis of the nozzle so that the jets will have both a spiral direction and an 70 expanding tendency, and thus give the most thorough cleansing action. The projection 12 acts in some degree to direct the water outward from the axis of the tip, as it flows from the bore 6 into the bore 7, past 75 the shoulder 8; and thus to the inner ends of the ducts or recesses 11.

Our syringe is particularly adopted for vaginal use but can of course be made for other passages of the body as well. 80

Having described our invention, what we believe to be new and desire to secure and protect by Letters Patent of the United States is:

A nozzle for a spray syringe comprising 85 a removable tip having a bore terminating at a shoulder therein, a neck attached to the tip and having a relatively smaller bore therethrough beginning at said shoulder, a disk fixed inside the first-named bore and 90 spaced from the shoulder, the periphery of the disk tightly engaging the inside of the tip, the disk having recesses in its circumference to provide spiral ducts, and a head presenting a conical deflecting surface to 95 the outlet ends of said ducts and having a shank extending through the disk and projecting into the bore of said neck.

In witness whereof, we have signed our names to this specification this 10th day of 100 October 1922.

ISAAC Q. GURNEE.
ALBERT A. SMITH.
